UNITED STATES PATENT OFFICE.

FREDERICK MITCHELL, OF BROOKLYN, NEW YORK, ASSIGNOR OF ONE-HALF TO
CHARLES McCABE FORD, OF BROOKLYN, NEW YORK.

THEATRICAL LAMP.

1,417,935.

Specification of Letters Patent. Patented May 30, 1922.

Application filed June 18, 1921. Serial No. 478,740.

To all whom it may concern:

Be it known that I, FREDERICK MITCHELL, a citizen of the United States, and resident of the borough of Brooklyn, in the county of 5 Kings and State of New York, have invented certain new and useful Improvements in Theatrical Lamps, of which the following is a specification.

This invention relates to lamps of the class 10 known as theatrical lamps, and my improvements are directed to a lamp structure of such character as to be capable of service either for spot light purposes, or as an open light.

Heretofore separate lamp structures have been necessary to respectively provide the 15 spot light effect and the open light effect, which has entailed the expense for two installations; whereas, by combining the means 20 for producing these two different light effects in a single lamp organism, I am enabled to save a considerable proportion of the initial cost, besides securing the advantages that ensue when only a single lamp structure 25 has to be handled and cared for, in place of two.

The means whereby I have been enabled 30 to achieve the dual light effect referred to comprise a lamp casing containing a light organism, such as opposed carbons with their feed mechanism, and reflector; said casing having a lens portion with focusing means, for the spot light effect, and flared portion for open light effect.

The light organism is movably mounted in 35 the casing, so that it may be caused to co-act either with the lens portion of the lamp, or with the flared portion thereof, and the lamp structure generally is adapted for practical operation both as a spot light and an 40 open light.

Other features and advantages of my invention will hereinafter appear.

Figure 1 is a side sectional elevation of 45 my improved lamp.

Fig. 2 is a section on the line 2-2 of Figure 1.

Fig. 3 is an end view of Figure 1 looking toward the lens portion thereof, and

50 Fig. 4 is an opposite end view of Figure 1.

In carrying out my invention I provide a rectangular casing 1, having an upper extension 2 and a lower extension 3. At one end of said casing 1 there is fitted a lens 4,

and at its opposite end I provide a flared 55 extension 5.

Mounted in bearings 6, 6, carried by the base of casing 1, is a square shaft 7, which serves as a support for a sleeve 8, that is 60 slideable along said shaft. Said sleeve 8 carries a standard 9, which terminates in a socket portion 10, engaging in swivelled relation, one end of an arm 11, that constitutes the support for the light organism.

Said light organism, in the example herein illustrated, consists of the opposed carbons 12, 12, carried by sockets 13, 13, that themselves are adjustably extended out from insulated joints 14 forming part of a frame 15, which is connected to and carried by arm 11. 65

At 16 I have shown the vertical adjustment member for carbon feed, said member being a rod having knurled head 17, and having, at different portions of its length, opposite threads in engagement with similarly 75 opposed threads in collar portions 18, 18, which collar portions respectively have apertured extensions 19, 19, whereby they may slidably engage with a guide rod 20.

A reflector, carried by frame 15, and located at one side of the arc produced between the carbons 12, 12 is provided for the purpose of directing the light rays outwardly.

The arm 11, carrying the light organism 85 aforesaid, is capable of swinging upwardly in either direction through 180 degrees, between the horizontal position of its operativeness as an open light, indicated in full lines in Fig. 1, and the horizontal position 90 shown in the same figure in dotted lines, in which latter position it becomes operative, by means of co-action with lens 4, as a spot light, thus combining in the one lamp structure the two functions of an open light and 95 a spot light.

The swivel joint 10 is so devised, as by means of a stop 21, that the arm 11 is brought to rest when at its horizontal position, in either direction, and thus is capable 100 only of swinging upwardly from the horizontal plane. By these means, however, the light organism is reversible so that it may be caused to co-act, at will, with either the spot light or open light directing means, 105 this being the main purpose of my invention.

For co-action with the lens, when the

light organism is faced in the direction thereof, proper focusing of the light is effected by moving the light organism nearer to or more distant from the lens, 5 this longitudinal adjustment being accomplished by sliding the sleeve 8 along the bar or rod 7. The handle 22 upon member 8 permits the adjustment to be effected.

Also, by means of the hand holes 23, 24, 10 respectively in the lower and upper extensions of the casing, at one end thereof, the operator is enabled to swing the light organism from one to the other of its operative positions; to adjust the focus; and to 15 actuate the feed of the carbons.

The lamp is supported upon the base 25 by a telescoping shaft 26, working in tubular portion 27, controlled by set screw 28; also being revoluble under the control 20 of a set screw 29; while the angular adjustment of the lamp is controlled by a suitable joint 30; these features being of usual character. The usual rheostat, for reducing the voltage supplied to the lamp, 25 is shown at 31, and the current controlling switch is indicated at 32.

When the lamp is being utilized for spot light purposes the flared end portion thereof is to be covered, to prevent escape 30 of light rays through the opposite, flared end portion of the lamp. For this purpose I provide a cover 33, here shown as hinged at 34 to said portion 5, and capable of closing over the exposure at that end. But 35 when the light organism directs the light out through the open, flared end 5, then the lens portion should be covered, and, as an example of suitable covering means, I have shown a cap 35 which is capable of 40 being fitted over the lens portion of the lamp, to obscure the light at that end.

Slide ways 36, provided respectively at the flared and lens containing portions of

the lamp, serve the usual purpose of receiving colored slides, for modifying the light 45 emitted.

Variations within the spirit and scope of my said invention are equally comprehended by the foregoing disclosure.

I claim:

1. A lamp comprising a casing having light concentrating means at one end and light spreading means at its opposite end, and a longitudinally adjustable light organism, reversibly mounted in said casing, to co-act respectively with said light concentrating means and light spreading means. 50

2. A lamp comprising a casing provided at opposite ends, respectively, with light concentrating means and light spreading means, a light organism, a mount therefor, and a support upon which the mount is longitudinally adjustable, the light organism engaging the mount reversibly, whereby it may co-act either with the light concentrating means or the light spreading means. 60

3. A lamp comprising a casing provided at opposite ends, respectively, with light 70 concentrating means and light spreading means, the casing provided with upper and lower enlargements, each having a hand-hole, a light organism, a mount therefor, and a support upon which the mount is 75 longitudinally adjustable, the light organism engaging the mount reversibly, a part thereof being adapted to swing through the enlargements, whereby the light organism may co-act with the light concentrating 80 means or the light spreading means.

Signed at the borough of Manhattan, in the city, county and State of New York, this 17th day of June, A. D. 1921.

FREDERICK MITCHELL.
